UNITED STATES PATENT OFFICE.

HARRY COHN, OF BROOKLYN, NEW YORK, ASSIGNOR TO HYGRADE LIGHTING FIXTURE CORPORATION, OF BROOKLYN, NEW YORK, A CORPORATION OF NEW YORK.

DESIGN FOR A COMBINED WALL-BRACKET AND SOCKET-COVER FOR LIGHTING-FIXTURES.

58,885.

Specification for Design.

Patented Sept. 6, 1921.

Application filed January 13, 1921. Serial No. 437,089. Term of patent 7 years.

To all whom it may concern:

Be it known that I, HARRY COHN, a citizen of the United States, residing at Brooklyn, in the county of Kings and State of New York, have invented a new, original, and ornamental Design for a Combined Wall-Bracket and Socket-Cover for Lighting-Fixtures, of which the following is a specification, reference being had to the accompanying drawing, forming part thereof.

Figure 1 is a side elevation of a wall bracket and socket cover for lighting fixtures; and Fig. 2 is a front view of the same.

I claim:

The ornamental design for a combined wall-bracket and socket cover for lighting fixtures, as shown.

HARRY COHN.
